[57] CLAIM

The ornamental design for a pocket medication controller, as shown and described.

DESCRIPTION

FIG. 1 is a perspective view of the pocket medication controller in a folded state thereof;

FIG. 2 is a perspective view of the pocket medication controller in an unfolded state thereof;

FIG. 3 is a side view of the pocket medication controller in its unfolded state;

FIG. 4 is a front side view of the pocket medication controller in its unfolded state;

FIG. 5 is a rear side view of the pocket medication controller in its unfolded state;

FIG. 6 is a side view of a timing pin of the pocket medication controller;

FIG. 7 is a top plan view of the pin of FIG. 6;

FIG. 8 is a bottom plan view of the pin of FIG. 6;

FIG. 9 is a rear side view of the pocket medication controller in its folded state;

FIG. 10 is a side view of the pocket medication controller in its folded state;

FIG. 11 is a front side view of the pocket medication controller in its folded state;

FIG. 12 is a top plan view of the pocket medication controller in its folded state;

FIG. 13 is a bottom plan view of the pocket medication controller in its folded state;

FIG. 14 is a bottom plan view of the pocket medication controller in its unfolded state; and,

FIG. 15 is a top plan view of the pocket medication controller in its unfolded state.
